ATTORNEYS

UNITED STATES PATENT OFFICE.

GRACE H. LANGE, OF SAN FRANCISCO, CALIFORNIA.

DESIGN FOR A TOY FIGURE.

54,104.

Specification for Design.

Patented Nov. 4, 1919.

Application filed April 16, 1918. Serial No. 228,972. Term of patent 7 years.

To all whom it may concern:

Be it known that I, GRACE H. LANGE, a citizen of the United States, and a resident of the city and county of San Francisco, State of California, have invented a new, original, and ornamental Design for a Toy Figure, of which the following is a specification, reference being had to the accompanying drawings, forming part thereof.

Fig. 2 is a side view of the figure.

I claim:

The ornamental design for a toy figure, substantially as shown.

GRACE H. LANGE.

Witness:

H. G. PROST.
